UNITED STATES PATENT OFFICE.

CHARLES LEDERHOS, OF NEW YORK, N. Y.

DESIGN FOR AN OIL-STOVE.

SPECIFICATION forming part of Design No. 25,462, dated May 5, 1896.

Application filed January 18, 1896. Serial No. 576,042. Term of patent 14 years.

To all whom it may concern:

Be it known that I, CHARLES LEDERHOS, a citizen of the United States, residing in the city, county, and State of New York, have invented and produced a new and original Design for Oil-Stoves, of which the following is a specification.

The leading feature of my design is an oil-stove of substantially the configuration and representation shown in the accompanying drawings, in which—

Figure 1 is a side elevation of an oil-stove embodying my design. Fig. 2 is a transverse section on line 22 thereof. Fig. 3 is a broken-away plan view of the oil-stove.

In the drawings the frame of the stove is shown as consisting of bowed end sections A B, which are connected by platforms C D, the platform C extending from about the bottom of one end section to the bottom of the other and the platform D extending from the top of one section to the top of the other and being pierced with reticulated or grated open-

ings E F. Cylindrical burners G are located beneath these openings and extend upward 25 from the lower platform C and terminate in chimneys H, which extend to the upper platform. Depending from the upper platform D is a shield or curtain I, which is inclined toward the middle line of the stove—that is 30 to say, in the direction of the burners. Located beneath the shield are cylindrical founts J J', from which struts or legs b b b extend downwardly and laterally. These founts are located between the end sections A B and extend horizontally from end section to end section.

What I claim is—

The design for an oil-stove, substantially as herein described and illustrated in the accompanying drawings.

CHARLES LEDERHOS.
